UNITED STATES PATENT OFFICE.

FRANK B. GOODALE, OF IOLA, KANSAS

MOTOR-STAND.

1,296,074.

Specification of Letters Patent. Patented Mar. 4, 1919.

Application filed August 14, 1918. Serial No. 249,878.

To all whom it may concern:

Be it known that I, FRANK B. GOODALE, a citizen of the United States, residing at Iola, in the county of Allen and State of 5 Kansas, have invented a new and useful Motor-Stand, of which the following is a specification.

This invention relates to a motor stand for holding the motor of an automobile 10 while being repaired, one of its objects being to provide a stand on which motors of different sizes may be mounted and which will hold the motor firmly while a reamer connected to the mechanism of the machine, 15 can be utilized for dressing all of the bearings simultaneously, thereby insuring perfect alinement and allowing the shaft of the engine to be placed in the bearings immediately thereafter to smooth the bearings. 20 Heretofore it has been the practice to separately dress the bearings, at the expenditure of considerable time and labor, after which the shaft has been placed in position and, in order to prevent breaking of axles, gears, 25 and other parts, the machine has been hauled by another machine until the bearings have been properly smoothed. Obviously, therefore, a considerable saving of time is accomplished by the present improvements which 30 permit the shaft to be operated by the machine immediately after the dressing operation.

A further object of the invention is to provide a motor stand which will hold the 35 motor at various angles, thus to enable repairs to be made to different parts thereof, facilitate grinding of the valves, etc.

With the foregoing and other objects in view the invention consists of certain novel 40 details of construction and combinations of parts which will be hereinafter more fully described and pointed out in the claims, it being understood that various changes may be made in the construction and arrangement of the parts without departing from the spirit or sacrificing any of the advantages of the invention as set forth in the appended claims.

In the accompanying drawings the preferred form of the invention has been shown.

In said drawings

Figure 1 is an elevation of the stand, the motor being shown thereon by dotted lines.

Fig. 2 is a plan view.

Fig. 3 is a section on line 3—3, Fig. 2.

Referring to the figures by characters of reference, 1 designates a table having an opening 2 therein into which ears 3 project from one wall of the opening. Brackets 4 are extended from the back of the table 60 and extend upwardly and laterally therefrom. Arranged between these brackets is a cross head 5 which is bowed from end to end and has its terminals connected to the brackets 4 by pivot bolts 6 or the like. A 65 split sleeve 7 is formed integral with the middle portion of the cross head and extends transversely thereof, this sleeve receiving a short shaft 8 provided at one end with an attaching head 9 from which extend spaced bolts 10. A clamping bolt 11 extends transversely through the split sleeve above the shaft 8 and by means thereof the sleeve can be clamped on the shaft 70 so as to hold it firmly against movement 75 relative to the cross head.

Standards 12 are mounted on the table beyond one end of the cross head 5 and a shaft 13 is journaled in them. A wheel 14 is secured to the shaft between the standards and connected to one end of the shaft 80 is a chuck for engaging and supporting a reamer. In the drawings the chuck has been shown at 15 and the reamer at 16. This reamer is of sufficient length to extend 85 through all of the bearings of a motor M.

The gear 14 is adapted to receive motion from a gear 18 secured to a shaft 19 which is journaled in one of the standards 12 and in an end standard 20. Pulleys 21 are 90 mounted on the shaft 19 and are adapted to be engaged by a drive belt, not shown. A guide 22 may be arranged adjacent these pulleys for supporting a belt shifter 23.

In using the device the motor to be repaired is placed on the table so that its bearings will aline with the center of the chuck 15. If elevation of the motor is necessary in order to bring its bearings into alinement with the chuck, plates or shims 100 may be placed thereunder as will be obvious. The motor is bolted to the table by bolts passing through the ears 3 and the head 9 is also bolted to the motor, the bolts 10 being utilized for this purpose. After the 105 motor has been positioned accurately the reamer 16 is inserted into the bearings and into engagement with the chuck. Thus when the shaft 13 is rotated all of the bearings will be dressed simultaneously and af- 110

ter the reamer has been withdrawn the shaft can be placed in the bearings and driven to smooth the bearings.

By releasing the motor from the table, 5 the cross head can be swung laterally and by tightening the pivots 6 the cross head with the motor connected thereto, can be held in any position to which it may be adjusted. By loosening the bolt 11 the shaft 10 8 will be free to rotate so that the motor can thus be tilted relative to the cross head to facilitate different kinds of work. Obviously after the motor has once been placed in position it can be shifted readily to different positions without being detached 15 from the stand and all necessary repairs, etc. can be made before it is removed. By swinging the cross head backwardly and outwardly from the stand it will hold the 20 motor in an inverted position and thus give convenient access to the bottom of the motor.

The reamer 16 is of such length as to extend through all of the bearings at one time 25 and can be made of different lengths and diameters to ream bearings of different sizes on engines of various makes.

What is claimed is:—

1. A motor stand including a table, a 30 cross head mounted to swing thereon, a shaft extending through and revoluble within the cross head, means for binding the cross head upon the shaft to hold the shaft against movement, and an attaching head 35 at one end of the shaft.

2. A motor stand including a table, a

cross-head mounted to swing relative thereto and having an integral split sleeve, a shaft slidably and revolubly mounted in the sleeve, an attaching head at one end of the shaft, and means for binding the sleeve upon the shaft.

3. A motor stand including a table, drive mechanism thereon including a chuck, brackets upon the table at one side, a cross 45 head between and pivotally connected to the brackets, a split sleeve integral with the cross head, a shaft slidably and revolubly mounted in the sleeve, an attaching head at one end of the shaft for holding a motor 50 with its bearings in line with the chuck, and means for binding the sleeve upon the shaft.

4. The combination with a table and brackets extending from one side thereof, 55 of a bowed cross head between and connected to the brackets, said cross head being mounted to swing to different positions relative to the table, a split sleeve integral with and extending transversely of the cross head, a shaft slidably and revolubly mounted in the sleeve, means for binding the sleeve upon the shaft, and an attaching head at one end of the shaft.

In testimony that I claim the foregoing 60 as my own, I have hereto affixed my signature in the presence of two witnesses.

FRANK B. GOODALE.
